UNITED STATES PATENT OFFICE.

JOHN G. NYBERG, OF PROVIDENCE, RHODE ISLAND, ASSIGNOR TO DOLAN & BULLOCK, A FIRM COMPOSED OF ARTHUR F. DOLAN AND FRED A. BULLOCK, OF ATTLEBORO, MASSACHUSETTS, AND WILLIAM G. BENNETT, OF PROVIDENCE, RHODE ISLAND.

CUFF BUTTON.

Application filed May 9, 1925. Serial No. 29,067.

To all whom it may concern:

Be it known that I, JOHN G. NYBERG, a citizen of the United States, residing at Providence, in the county of Providence and 5 State of Rhode Island, have invented certain new and useful Improvements in Cuff Buttons, of which the following is a specification.

This invention relates to an improved construction of cuff buttons of the separable type, and has for its object to provide a button of this character comprising stud and socket members, the stud member carrying 10 separable jaws to releasably engage the socket member and this stud member is also provided with an axially movable pin operable through its outer head for controlling the engaging and releasing actions of the jaw members with the socket member.

15 A further object of this invention is the provision of a pair of jaws in the stud member, each having an inwardly extending lip for engagement with an axially movable pin, the pin being recessed for the reception of 20 the lips of the jaw members to permit the jaws to move toward each other to released position.

25 A further object of this invention is to provide a spring acting upon the jaw members for moving these members toward each other when permitted by axial movement of the control pin.

With these and other objects in view, the invention consists of certain novel features 30 of construction, as will be more fully described, and particularly pointed out in the appended claims.

In the accompanying drawings,

35 Figure 1 is a side elevation partly in section illustrating the stud and socket members of a cuff button as locked together.

Figure 2 is a perspective view of one of the jaw members.

40 Figure 3 is a plan view illustrating the spring for moving the jaw members toward each other.

Figure 4 is a sectional view illustrating the spring in its operative position in relation to the jaw members.

45 Figure 5 is a side elevation partly in section illustrating the jaw members in releasing position.

Figure 6 is a sectional plan view taken on line 6—6 of Figure 5.

It is found in the practical operation and 55 construction of cuff buttons, of advantage to provide readily operable means whereby the button members are positively locked together so that they cannot be separated except by manual manipulation of a central 60 pin; and to accomplish this object, I have provided laterally movable jaws in the stud member acted upon by a spring for moving these jaws toward each other to contracted position, in which position they are adapted 65 to pass through the opening in the socket member, and I have provided an axially movable pin operable through the head of the stud member for spreading the jaw members into expanded gripping position 70 and for controlling the action of these jaw members; and the following is a detailed description of the present embodiment of this invention showing one construction by which these advantageous results may be accomplished:—

With reference to the drawings, 10 designates the stud member and 11 the socket member of the separable button, the socket member being provided with an outer head 12 and an inner head 13, the inner head 14 being provided with a plate 15, having a central opening 16 for the reception of projecting locking jaws 17 mounted in the stud member 10. The stud member is provided 85 with an outer head 18 and an inner head 19, the inner head being provided with a plate 20 having an opening 21 therein. Through this opening project the pair of jaws 17 flanged as at 22 and enlarged as 90 at 23 to prevent them from being dislodged from the opening 21. Each of the jaws is provided with an inwardly-extending lip 24 and an opening 25 for the reception of the ends 26 of an arcuate spring 27, which 95 spring tends at all times to move the jaws toward each other into the position shown in Figures 4, 5 and 6. An axially movable pin 28 extends between the jaws 17 normally in engagement with the inwardly-projecting lip 24 and serving to spread the jaws into locking position, as illustrated in Figure 1, and in order to permit the jaws to move to released position, the pin is recessed as at 29 so that an inward movement of the pin causes the recess to cooperate with the inwardly extending lips 24 to permit them to move toward each other 100 105

under the action of spring 27 into the position shown in Figure 5. The outer end of the pin extends up into the presser cap 30 and is held in extended position through action of spring 31, which forces the pin 28 outwardly to spread the jaws 16 into locking position. It will be readily apparent that upon movement of cap 30 inwardly the jaws will be permitted to move to contracted position under action of spring 27 and permit their free insertion or renewal into the socket member, and that when released the jaws will be expanded by the pin 28 into locking position.

15 My improved form of separable button is very simple and effective in construction and attractive in its appearance, and by its use the button members may be positively locked against inadvertent separation and 20 may be released to separate only by pressure upon the presser cap which extends through the outer head of one of the button members.

25 The foregoing description is directed solely towards the construction illustrated, but I desire it to be understood, that I reserve the privilege of resorting to all the mechanical changes to which the device is susceptible, the invention being defined and limited 30 only by the terms of the appended claims.

I claim:

35 1. A separable cuff button comprising stud and socket members, separable bodily movable jaws carried by said stud member for releasably engaging said socket member, means for positively forcing said jaws to contracted position, an axially movable pin in said stud member for controlling the action of said jaws, and means acting on said 40 pin for causing said pin to normally expand said jaws into their locking position.

45 2. A separable cuff button comprising stud and socket members, separable jaws carried by said stud member for releasably engaging said socket member, an axially slidable pin between said jaws and cooperat-

ing projection and recess means between said pin and jaws for moving said jaws to engaging position and permitting said jaws to move to released position upon different axial position of said pin.

3. A separable cuff button comprising stud and socket members, separable jaws carried by said stud member for releasably engaging said socket member, an inwardly-extending projection on said jaws, a spring engaging said jaws for moving them toward each other into contracted released position, an axially movable spring pressed pin extending between said jaw in engagement with said projection for holding said jaws in expanded gripping position, said pin being provided with a recess for receiving said jaw projections to permit said jaws to move toward each other into released position.

4. A separable cuff button comprising stud and socket members, a pair of bodily movable jaws in said stud member for engaging said socket member, each having an inwardly-extending projection, an annularly-recessed pin extending between said jaws engaging said projection to spread said jaws into engagement with the walls of said socket and axially movable to permit said projections to extend into said recess and said jaws move toward each other to contracted released position.

5. A separable cuff button comprising stud and socket members, separable jaws carried by said stud member for releasably engaging said socket member, an arcuate spring having engagement with said jaws substantially at diametrically opposite points for moving said jaws toward each other to released position, and an axially movable pin between said jaws for controlling their action.

In testimony whereof I affix my signature.

JOHN G. NYBERG.
